UNITED STATES PATENT OFFICE.

EDWIN T. WHIFFEN, OF NEW ROCHELLE, NEW YORK.

FOUNTAIN PEN.

Application filed March 4, 1922. Serial No. 541,066.

To all whom it may concern:

Be it known that I, EDWIN T. WHIFFEN, a citizen of the United States, and a resident of New Rochelle, in the county of West-
5 chester and State of New York, have invented a new and Improved Fountain Pen, of which the following is a full, clear, and exact description.

This invention has relation to fountain pens and refers more particularly to a fountain pen of the self-filler type.

The invention contemplates for one of its principal objects a self-filling fountain pen which affords a simple and effective means 15 for introducing the writing fluid into the barrel through the ink outlet or feeder opening whereby to obviate the necessity of removing the nib and feeder carrier during the filling operation.

20 As a further object the invention contemplates a filling element which consists of a plunger movable within the barrel for drawing the ink into the same and a plunger rod connected therewith and extending 25 through the head of the barrel to permit of the manipulation of the plunger.

The invention further contemplates in a fountain pen a self-filling means which is simple and compact in its structure to afford 30 a maximum ink receiving space and which is strong and durable in construction to obviate the necessity of constant repairs.

With the above recited and other objects in view, the invention resides in the novel 35 construction set forth in the following specification, particularly pointed out in the appended claims and illustrated in the accompanying drawings, it being understood that the right is reserved to embodiments other 40 than those actually illustrated herein to the full extent indicated by the general meaning of the terms in which the claims are expressed.

In the drawings—

45 Figure 1 is a longitudinal sectional view through a fountain pen constructed in accordance with the invention.

Fig. 2 is a similar view illustrating the operation of the filling means for introducing the ink into the pen.

50 Fig. 3 is a transverse sectional view taken approximately on the line 3—3 of Fig. 1.

Fig. 4 is an enlarged fragmentary sectional view illustrating the manner in which 55 the ink is fed to the pen nib when in writing position.

Referring to the drawings by characters of reference, 10 designates a pen barrel of tubular construction provided at its upper end with a closed head 11 having an exteriorly threaded portion 12 extending therefrom to engage and coact with an internally threaded closure cap 13. A nib carrier 14 is threaded in the opposite or lower end of the barrel and the same has associated therewith the feeder 15 and pen nib 16 arranged in the ink outlet or feeder opening 17. The lower extremity of the barrel is exteriorly threaded as at 18 to receive the usual detachable cap 19.

The filling means consists of a plunger head 20 having a peripheral packing 21 engaging the bore of the barrel and provided with a central opening 22 through which the inner or lower end of a tubular plunger rod 23 extends and is secure. The opposite end of the plunger rod extends through a central opening 24 in the head 11 and is engaged by an inner peripheral packing 25. The plunger rod is provided at its outer extremity with a removable manipulating handle 26 normally enclosed and concealed by the closure cap 13. The plunger rod is provided with an upper bore 27 and a reduced lower bore 28 communicating therewith and forming at the juncture with the bore 27 a shoulder 29. The upper bore normally is closed at its outer end by the body of the removable manipulating handle. Inlet and outlet openings 30 are provided in the plunger rod adjacent the shoulder 29 and establish communication between the interior of the barrel above the plunger head and the bore 27 of said plunger rod. A ball valve 31 is arranged in the bore 27 and normally seats on the upper end of the bore 28 to close the same when the pen is held in a vertical position with the nib end downward.

To fill the pen, the nib is inserted in the ink after the closure cap 13 is removed and plunger rod is pulled upwardly to draw the plunger head toward the upper end, thereby creating a suction in the barrel. The ink is thus drawn upwardly through the ink outlet or feeder opening 17 to introduce a supply in the barrel below the plunger. During this operation the ball valve 31 will seat on the upper end of the bore 28. The removable manipulating handle 26 is removed to permit escape of the air confined between the plunger and the head 11 and is replaced in position to close the bore 27 at

its outer end as soon as the upward movement or retraction of the plunger has been accomplished. To move the plunger downward to normal position and permit of the transfer of the ink from the under side of the plunger to the space above the same, the ball valve is lifted as the plunger descends, permitting the ink to flow through the bore 28 into the bore 27 and through the openings 30 into the barrel above the plunger. The closure cap 13 is then associated with the threaded portion 12 of the head 11 and the pen is ready for use. In use of the pen when held in writing position at the usual angle as illustrated in Fig. 4, the ball valve 31 is unseated from the upper end of the bore 28 and rests on the shoulder at the lower end of the bore 27 to permit the ink to flow from the bore 27 and the interior of the barrel above the plunger through the bore 28 to the ink outlet or feeder opening into the feeder and onto the nib.

I claim:

1. The combination with a fountain pen including a barrel having a feeding opening at one end, of a filling means comprising an axially movable plunger having an ink passage extending therethrough, a plunger rod connected thereto and extending through the opposite end of the barrel for manipulating the plunger, and means operable upon movement of the plunger away from the feeding opening to close the ink passage for creating a suction to introduce ink through the feeding opening into the barrel, said means being operable upon movement of the plunger in the opposite direction to open the passage to allow the ink to pass therethrough, said means being further operable when the pen is in writing position to uncover the passage to permit of the feeding of the ink therethrough.
2. In a fountain pen, a barrel open at one end and provided with a combined feeding and filling opening at its other end, a plunger reciprocable in the barrel, a tubular

plunger rod extending through said plunger and secured adjacent to one end to the latter, said plunger rod extending slidably through the closed end of the barrel, said plunger rod being provided with a lateral port adjacent to but spaced from the plunger and being provided with a valve seat located in the inner wall of the plunger rod between the lateral port and the said one end of the plunger rod, and a check valve disposed in the bore of the plunger rod in position to open toward the closed end of the barrel and being adapted to move to open position when the barrel is in writing position, said valve being adapted to cooperate with the valve seat when in closed position to prevent flow of fluid from the feeding and filling opening through the plunger rod to the lateral port.

3. In a fountain pen, a barrel open at one end and provided with a combined feeding and filling opening at its other end, a plunger reciprocable in the barrel, a tubular plunger rod extending through said plunger and secured adjacent to one end to the latter, said plunger rod extending slidably through the closed end of the barrel, said plunger rod being provided with a lateral port adjacent to but spaced from the plunger and being provided with a valve seat located in the inner wall of the plunger rod between the lateral port and the said one end of the plunger rod, and a check valve disposed in the bore of the plunger rod in position to open toward the closed end of the barrel and being adapted to move to open position when the barrel is in writing position, said valve being adapted to cooperate with the valve seat when in closed position to prevent flow of fluid from the feeding and filling opening through the plunger rod to the latter port, and a removable means for closing the tubular plunger rod at its second named end.

EDWIN T. WHIFFEN.
